UNITED STATES PATENT OFFICE.

AXEL H. ANDERSON, OF JAMESTOWN, NEW YORK.

GARMENT-HANGER.

1,119,135.

Specification of Letters Patent.

Patented Dec. 1, 1914.

Application filed April 22, 1914. Serial No. 833,752.

To all whom it may concern:

Be it known that I, AXEL H. ANDERSON, a subject of the Kingdom of Sweden, residing at Jamestown, in the county of Chautauqua and State of New York, have invented certain new and useful Improvements in Garment-Hangers, of which the following is a specification, reference being had to the accompanying drawings.

10 This invention relates to new and useful improvements in garment hangers and more particularly to a device which is adapted to be applied to the back of a theater chair or seats or chairs of a similar character, the 15 main object of the invention being the provision of a garment supporting device which can be readily applied to the back of a theater chair, whereby outer garments may be readily suspended therefrom, thus eliminating 20 the inconvenience of having to hold them or having to place them in the chair which is occupied.

Another object of the present invention is the provision of a device of the above character which will possess advantages in points of efficiency and durability, is inexpensive to manufacture and, at the same time, is simple in construction and operation.

With the above and other objects in view, 30 the invention consists in the novel features of construction, combination and arrangement of parts as will be hereinafter referred to and more particularly pointed out in the specification and claim.

35 In the accompanying drawing forming a part of this application, Figure 1 is a front elevation of a hanger constructed in accordance with my invention, illustrating the application of the same. Fig. 2 is an elevation 40 illustrating the manner of suspending the supporting arm. Fig. 3 is a sectional view of the hanger, taken on the line 3—3, Fig. 1. Fig. 4 is a detail sectional view taken on the line 4—4, Fig. 1. Fig. 5 is a side elevation of the showing illustrated in Fig. 2. Fig. 6 is a detail front elevation illustrating 45 a slightly modified form of the device; and Fig. 7 is a sectional view taken on the line 7—7, Fig. 6.

50 In carrying out my invention, I provide two supporting plates which are indicated by the numerals 1 and 1', said plates being of substantially similar design and provided with screw openings 2, whereby they may 55 be readily secured to the back of the seat and arranged in spaced relation, as indi-

cated in Fig. 1. Each of the supporting plates are provided upon the outer face thereof with the spaced bearings 3 and separated by the longitudinal slot 4. Suspended from the supporting plate 1', is a movable arm 5, the upper end of which is provided with outwardly projecting alined lugs 6 adapted to be arranged within the bearings 3, while the arm 5 projects out through the slot 4. From this it will be apparent that the arm 5 is pivotally connected to the plate 1' and may be swung outwardly in any desired angle. After the upper end of the arm has been disposed within the slot 4, the upper edges of the material forming the slot is preferably bent inwardly to prevent accidental removal of the upper end of the arm.

The outer end of the arm 5 is bifurcated to form two spaced perforated ears 7, between which is arranged the perforated end of the supporting arm 8. It will be noted that one of the ears 7 project beyond the end of the opposite ear and terminates into a point which, after the arm 8 has been arranged between the ears is bent upon itself and extends transversely across the bifurcation in the lower end of the arm 5, so as to present a smooth and unbroken surface, whereby the clothing will not catch upon either of the ears 7 and also to prevent any accidental removal of the end of the arm 8 from between the ears. The perforated end of the arm 8 is securely held in position between the ears 7 by means of the transverse pin 9 which is preferably in the form of a rivet, as disclosed in Fig. 3. The other end of the arm 8 is provided with an enlarged head 10 which, when the arm is suspended within the supporting hook 11, 95 is adapted to prevent longitudinal movement of the bar. The hook 11 is formed upon the lower end of a supporting rod 12, the upper end of which is provided with the outwardly projecting alined lugs 13 adapted to be arranged within the bearings 3 formed upon the plate 1. From this it will be apparent that when the bar 8 is suspended from the arm 5 and the rod 12, the same may be readily swung outwardly so that the garments 100 may be engaged thereover.

In Fig. 6, I have illustrated a slightly modified form of means for pivotally mounting the arm 5 and the rod 12. In this form of the invention, perforated spaced ears 14 110 are formed upon the outer face of the plates and the upper ends of the arms 5 and 12

are provided with circular portions 15 which are adapted to be arranged between the ears 14 and pivotally secured in position by means of the transverse pins 16.

5 It will be apparent from the above that the operation of my improved garment hanger is as follows:—When it is desired to suspend a garment of any character therefrom, the head or end of the bar 8 is re-
10 moved from the hanger 13 and the arm 5 swung outwardly, carrying the bar 8 with it, so that any form of garment may be readily engaged over the bar. The bar is then swung inwardly over the seat and the end suspended over the hook 11. It will be un-
15 derstood that a garment of any thickness may be suspended from the bar as the supporting arm 5 and the rod 12 both move outwardly simultaneously after the bar 8
20 has been engaged with the hook 11.

From the above description taken in connection with the accompanying drawing, it will be readily apparent that I have provided a simple and durable garment hanger
25 which can be quickly and readily applied to the back of theater chairs and the like or readily removed therefrom. It will also be apparent that any form of garment may be readily mounted upon the hanger or re-
30 moved therefrom. The device, as herein shown and described, is extremely simple in

construction and can be manufactured and placed upon the market at a comparatively low cost.

While I have shown and described the 35 preferred form of my invention, it will be obvious that various changes in the details of construction and in the proportions may be resorted to for successfully carrying my invention into practice, without sacrificing 40 any of the principles of the invention, or departing from the scope of the appended claim.

Having thus described this invention, 45 what I claim is:—

A device of the class described including spaced supporting plates, a supporting arm having one end pivotally mounted upon one of said plates, a supporting bar having one end pivotally connected to the lower end of the arm, a second arm pivotally connected with the plate on the opposite side, a hook suspended from the second supporting arm and adapted to receive the other end of the supporting bar, as and for the purpose set 50 forth.

In testimony whereof I hereunto affix my signature in the presence of two witnesses.

AXEL H. ANDERSON.
